UNITED STATES PATENT OFFICE.

JOHN J. EWING, OF RICHMOND, VIRGINIA.

DRAFT-GEAR.

1,180,707.

Specification of Letters Patent. Patented Apr. 25, 1916.

Application filed May 8, 1915. Serial No. 26,758.

To all whom it may concern:

Be it known that I, JOHN J. EWING, a citizen of the United States, and a resident of Richmond, county of Henrico, and State 5 of Virginia, have made and invented certain new and useful Improvements in Draft-Gears, of which the following is a specification.

This invention relates to draft gears and 10 it consists in the novel features hereinafter described and claimed.

An object of the invention is to provide a draft gear of simple and durable structural arrangement the parts being so assembled 15 as to permit of relative movement under the influence of springs, which movement will relieve the car or vehicle to which the gear is applied from such jar when the engine with which the car is connected is started or 20 backed or checked in its movement.

Another object of the invention is to improve the form of yoke for retaining the springs and with this object in view the yoke is preferably in the form of a body having 25 integral parts with pockets provided in the body, the said pockets being vertically disposed, that is to say the pockets are opened at their upper end and the springs are insertible in the pockets through the open 30 ends thereof. Means are provided upon the yoke for bridging the open upper ends of the pockets whereby the springs are effectually held in position therein. Followers are also located in the pockets and the said followers 35 coöperate with the springs to check or absorb such shocks incidental to starting and stopping the train whereby the cushioning effects hereinbefore referred to are obtained.

Another object of the invention is to provide the yoke with keys disposed transversely thereof and located in slots provided in the yoke. The end portions of the slot extend within the ends of the pockets 45 and the said followers bear against the opposite edges of the said keys at points between the ends of the keys. The beams of the center sill of the car body are provided with openings which snugly receive the end 50 portions of the said keys whereby the keys are practically fixed with relation to the

body of the car. Consequently the yoke may move with relation to the center sill of the car and with relation to the said keys but the springs and the followers serve to 55 maintain the yoke at a predetermined normal position with relation to the sill and the movement of the yoke with relation to the sill does not occur until the yoke is subjected to sudden or abnormal shock or pressure. 60

Another key is provided upon the yoke and is practically held against movement with relation thereto. The end portions of the last mentioned key are movably received 65 in slots provided in the beams of the sill and the last mentioned key serves as a means for connecting the shank of the coupler with the yoke.

In the accompanying drawings:—Figure 70 1 is a top plan view of the draft gear. Fig. 2 is a vertical longitudinal sectional view of the same cut on the line 2—2 of Fig. 1. Fig. 3 is a similar view cut on the line 3—3 of Fig. 1. Fig. 4 is a perspective view of 75 the yoke which constitutes the principal features of the invention. Fig. 5 is a horizontal sectional view taken on line 5—5 of Fig. 2. Fig. 6 is a transverse sectional view of the draft gear cut on the line 6—6 of 80 Fig. 5. Figs. 7 and 8 are transverse sectional views of the yoke showing modified arrangements of the bridges thereof. Fig. 9 is a perspective view of a modified form of the yoke and showing but a single pocket. 85 Fig. 10 is a vertical, longitudinal view of Fig. 11 is a transverse sectional view. 90

As illustrated in the accompanying drawings the sills to which the draft gear is applied, consist of the two parallel beams 1 of the standard form. The said beams are provided at spaced intervals with elongated openings 2 and in advance of the said openings with slots 3. The said slots and openings are in longitudinal alinement and they receive keys 4. The cotter pins 5, or other suitable securing devices, pass through the end portions of the said keys and are disposed adjacent the outer surfaces of the beams 1 and serve as means for preventing 95 100

the said keys from moving transversely with relation to the said beams. The openings 2 snugly receive the keys 4 as best illustrated in Fig. 5 of the drawing where the key 5 which is located in the slots 3 is less in transverse breadth than the length of the said slots and consequently the said key may move along the slots as will be explained hereinafter. A coupler shank 6 is 10 provided with an opening 7 which snugly receives the intermediate portion of the key 4 located in the slots 3. The said shank and the form of coupler head attached thereto may be of any usual or standard pattern.

15 The yoke which constitutes an essential feature of the present invention includes a body of general parallelepiped configuration and the portions thereof constitute an integral unitary structure preferably composed of cast metal. The body of the yoke includes side portions 9 which extend the full length of the body and are disposed parallel to each other and spaced from each other. The side portions 9 are connected 20 by cross webs 10, two of which are located in the vicinity of the ends of the side portions 9 and the other at a line intermediate the said end webs. The webs 10 are spaced from each other and the spaces or recesses 25 occurring between the webs constitute pockets 11 adapted to receive springs and followers hereinafter described. The body 8 is provided at its lower or under side with integral bridge strips 12 which connect the 30 cross webs 10 together and which are disposed midway between the side portions 9 and spaced from the same. Upstanding lugs 13 are provided upon the cross webs 10 at the upper surfaces thereof and the said lugs 35 are provided with openings adapted to receive detachable retaining bars 14. After the said bars are inserted through the openings of the lugs their end portions are angularly disposed as at 15 whereby the said 40 bars are held against longitudinal movement in the lugs. If desired in lieu of forming the bridge strips 12 integral with the body 8 of the yoke, lugs and bars 13' and 14' similar to the lugs and bars 13 and 14 45 just described may be provided at the under side of the said body for bridging the pockets 11.

The body 8 of the yoke is provided with transversely disposed slots 16, 17 and 18. 50 These slots traverse the length of the cross webs 10 and the forward end portions of the slots 16 extend in advance of the rear side of the rearmost pocket 11. The rear end portions of the slots 16 are continued 55 into the rear extremities 19 of the side portions 8 as shown in Fig. 4 of the drawing. The opposite ends of the slots 17 extend beyond the opposite side of the intermediate cross web 10 and consequently overlap the 60 end portions of the adjacent pocket 11. The 65

forward end of the slot 18 terminates approximately at the forward edge of the foremost cross web 10 while the rear ends of the slots 18 project behind the rear side of the foremost cross web 10 and overlap the 70 forward portion of the foremost pocket 11. The keys 4 which are snugly received in the openings 2 in the beams 1 of the center sill extend through the slots 16, 17 and 18, but inasmuch as the slots are longer than the 75 transverse breadth of the said keys the body 8 may move transversely with relation to the said keys.

Followers 20 are located in the pockets 11 and are positioned one at each end of each 80 pocket and one against the edge of the adjacent key 4 which are held in the openings 2. Springs 21 are located in the pockets 11 between the followers 20 therein and the said springs are under slight compression 85 with a tendency to hold the followers 20 in close contact with the edges of the adjacent keys 4. The springs 21 are of convoluted configuration and are made sufficiently heavy to withstand the normal, and cushion 90 the sudden jars and excessive strains to which they are subjected while the car is in motion.

The forward extremities of the side portions 9 of the body 8 are provided with 95 openings 22 which snugly receive the key 4 which is located in the slots 3 of the Fig. 1. Therefore a simple and durable means is provided for securely and effectually connecting the shank of the coupler with the 100 yoke and the yoke moves longitudinally in unison with the longitudinal movement of the coupler shank. In view of the fact that the springs 21 are interposed between the 105 followers which bear directly against the edges of the keys 4 received in the openings 3 when the body 8 is moved longitudinally the springs 21 are compressed and consequently the effect of a sudden jerk or jar is cushioned by the action of the springs if 110 the car is being moved in a forward or rearward direction. In either instance the springs 21 are compressed and a cushioning effect is had.

While the arrangement of the pockets 11 115 as shown in the drawings (Figs. 1 to 8 inclusive) is in what is generally known a tandem relation, that is to say, one pocket is located in advance of the other, it is to be understood that the number of pockets may 120 be reduced without departing from the spirit of the invention as expressed in the claims. In fact in some instances a single pocket may be all that is necessary or required as shown in Figs. 9 and 10. It will 125 be noticed that in this instance the yoke is similar to the yoke with the tandem pockets with the exception that only one pocket is shown and the central slot and partition 17 is naturally dispensed with. Also as shown 130

in Figs. 10 and 11 are shown lugs and bars 13' and 14' similar to the ones used on the top of the yoke although any of the forms mentioned may be equally as well used. The 5 two end portions however are similar to the end portions of the yoke shown in the other construction.

In the event that any one of the springs 21 should break or become defective, it is 10 necessary only to remove the bar 14 which spans that particular pocket when the impaired spring may be removed from the pocket by lifting the same out and a new spring may be inserted into the pocket 15 through the top therein instead. In view of the fact that the pockets are open at their lower sides they cannot accumulate dust or other foreign substance which would wedge 20 between the convolutions of the springs and reduce their resiliency or ability to contract when subjected to strain.

From the above description taken in conjunction with the accompanying drawing it will be seen that a draft gear of extremely 25 simple and durable structure is provided. A minimum number of parts are employed and in the main minute structure is avoided consequently the gear may be subjected to extremely rough use and under adverse 30 conditions without danger of being broken or disarranged to an extent to impair its usefulness and destroy its operative function. In other words the gear is a substantial and economical substitute for the more 35 elaborate and expensive draft gear now in general use and when operated will be equally as satisfactory.

Having thus described my invention what is claimed is:—

40 1. A yoke for a draft gear comprising a body having side portions and integral cross webs, there being provided between the side portions and the cross webs a series of 45 spaces which constitute pockets, the side portion having extremities which project beyond the rear side of the rearmost cross web, the body having slots which traverse the length of the cross webs and which extend through the side portion, the ends of 50 the slots extending beyond the sides of the cross webs and overlapping the ends of the pockets, the slots at the rearmost cross web projecting at their rear ends into the said rear extremities of the side portions.

55 2. A draft gear comprising a yoke consisting of side portions and cross webs to thereby form a pocket, said side portions provided at their forward and rearward ends with transverse openings, the transverse opening at the rearward end extending also into said pocket, a key snugly received in the first of said openings, a coupler mounted upon the key between the side portions of the yoke, means for slidably 60 supporting the end portions of the key and

a second key extending in the transverse opening in the rearward end of said yoke and a portion of said key free to move inward and outward in said pocket and removable means located above and below 70 said pocket for retaining the spring in said pocket.

3. A yoke for a draft gear comprising a body having spaced side portions and integral cross webs the spaces between the side 75 portions and the cross webs constituting pockets adapted to receive springs and followers, the body portion being provided with slots which traverse the length of the cross webs and extend through the side portions, the ends of the slots extending beyond the sides of the webs and overlapping the ends of the pockets, substantially as described.

4. A yoke for a draft gear comprising a 85 body having side portions and integral cross webs, there being provided between the side portions and the cross webs a series of spaces which constitute pockets, the side portions having extremities which project 90 beyond the rear side of the rearmost cross web and extremities which project beyond the foremost side of the foremost cross web, the body having slots which traverse the length of the cross webs and which extend 95 through the side portions, the ends of the slots extending beyond the sides of the cross webs and overlapping the ends of the pockets, the slots at the rearmost cross webs projecting at their rear ends into the rear extremities of the side portions, substantially 100 as described.

5. A draft gear comprising a yoke having pockets, springs located in the pockets, followers located in the pockets, cross keys 105 slidably mounted in the yoke and located beyond the opposite ends of the springs and projecting through the extension thereof, means for holding the cross keys at fixed positions whereby the yoke may be moved 110 with relation to the cross keys when the springs are compressed, said yoke being provided at its ends with openings, a cross piece snugly received in the last mentioned openings, a coupler connected with the last mentioned key and means for supporting the last mentioned key whereby the said key may move with the coupler, substantially 115 as described.

6. A yoke for a draft gear comprising a 120 body having spaced side portions and an integral cross web located at a distance from the forward ends of said side portions to form a space adapted to receive the end of a coupler shank, said forward ends provided with a longitudinally extending slot, a second integral cross web located near the opposite ends of said side portions, the space between said cross web constituting a pocket to receive a spring and followers, the 125 130

said side portions provided with slots which
traverse the length of the cross webs and ex-
tend through the side portions, the adjacent
sides of the slots extending beyond the sides
5 of the webs and overlapping the ends of the
pocket.

Signed at Richmond and State of Vir-
ginia this 3rd day of May A. D. 1915.

JOHN J. EWING.
